D11-72* OR D11-766 EX

UNITED STATES PATENT OFFICE.

CHARLES Z. DE YOUNG, OF PHILADELPHIA, PENNSYLVANIA.

DESIGN FOR AN ORNAMENTAL PIN.

SPECIFICATION forming part of Design No. 11,766, dated May 11, 1880.

Application filed April 3, 1880. Term of patent 7 years.

To all whom it may concern:

Be it known that I, CHARLES Z. DE YOUNG, a citizen of the United States, residing in the city and county of Philadelphia, and State of Pennsylvania, have invented and produced a new and original Design for a Piece of Jewelry known as a "Scarf," "Breast," "Shawl," "Lace," or other Pin, of which the following is a specification, reference being had to the accompanying photographic illustration, forming part thereof.

A represents the head or body of the piece, and B the attaching-pin secured thereto. The head or body A is of the form of a miniature locomotive-engine, and produces a neat and attractive design, suggestive of the business of engineers and other employés of railway companies, &c.

I claim—

The design for a jewelry-pin, consisting of the head or body A, of the form of a miniature locomotive-engine, and the attaching-pin B, as shown and described.

C. Z. DE YOUNG.
